UNITED STATES PATENT OFFICE.

EDWARD KAYE, OF MONACA, PENNSYLVANIA.

DESIGN FOR A CHIMNEY.

SPECIFICATION forming part of Design No. 29,836, dated December 20, 1898.

Application filed November 25, 1898. Serial No. 697,464. Term of patent 7 years.

To all whom it may concern:

Be it known that I, EDWARD KAYE, a citizen of the United States, residing at Monaca, in the county of Beaver and State of Pennsylvania, have invented a certain new Design for Chimneys for Incandescent Gas-Lights; and I do hereby declare the following to be a full, clear, and exact description of the invention, such as will enable others skilled in the art to which it appertains to make and use the same.

This invention has relation to a new and original design for gas or lamp chimneys, and is particularly adapted for chimneys used with gas-burners of the well-known type of Welsbach burners.

The design which constitutes the subject-matter of the application is shown in the accompanying drawings, in which—

Figure 1 is a top view, and Fig. 2 a side elevation, of a chimney embodying my invention.

The chimney comprises a body part and a neck part, the neck part flaring outwardly from the body part and being formed with corrugations or flutings, as shown.

Having thus described my invention, what I claim is—

The design for a chimney or similar article herein shown and described.

In testimony whereof I affix my signature in presence of two witnesses.

EDWARD KAYE.

Witnesses:

Wm. H. BLACK,
E. P. GILLESPIE.
